UNITED STATES PATENT OFFICE.

JOHN C. BAUMER, OF ROCHESTER, NEW YORK, ASSIGNOR TO HOMER STRONG, OF ROCHESTER, NEW YORK.

METHOD OF MAKING NEEDLES FOR FRUIT SEEDERS.

Application filed April 18, 1922. Serial No. 554,699.

To all whom it may concern:

Be it known that I, JOHN C. BAUMER, a citizen of the United States, residing at Rochester, in the county of Monroe and 5 State of New York, have invented certain new and useful Improvements in Methods of Making Needles for Fruit Seeders, of which the following is a specification.

The object of this invention is to provide 10 a new and improved method of making needles for use in fruit seeders.

This and other objects of the invention will be fully illustrated in the drawing, described in the specification and pointed out 15 in the claim at the end thereof.

In the drawing:

Figures 1 to 5 inclusive are detail sectional views of the rod from which the needle is formed, the successive figures illustrating the evolution of the needle from the 20 blank rod to the finished product.

Figure 1 shows the rod with a hole therein drilled from the end.

Figure 2 shows the end of the rod counter- 25 sunk.

Figure 3 shows the rod with the hole plugged.

Figure 4 shows the finished needle.

Figure 5 is a vertical transverse section of 30 the finished needle.

Figure 6 is a horizontal section on the line 14^x—14^x of Figure 3.

Figure 7 is a horizontal section on the line 15^x—15^x of Figure 4.

35 In the drawing, like reference numerals indicate like parts.

In the construction of the needle 40 lies the secret of the success of a fruit seeding machine. This needle is made of five individual blades 41 which are formed up out of 40 a single solid rod in the following manner.

A steel rod 70 of circular cross section and of suitable length is first drilled at one end to a suitable depth to provide an elongated 45 hollow center or pocket 71 therein. This pocket will be as long as the flexible part of the blade to be formed thereon. The end of the rod is then counter sunk as shown in Figure 10 to form the inwardly slanting 50 tips of the blades. This pocket is then temporarily plugged up by the rod or pin 72 as shown in Figure 11. After this is done the rod 70 is ready to be operated upon to form the individual blades at one end thereof.

55 After this is done the rod is suitably mount-

ed so that a milling cutter or other suitable cutting tool can be moved lengthwise of the rod to cut it into slits or tines beginning at the countersunk end thereof. In this way and for this purpose five equally spaced longitudinal channels are cut into the perimeter of the plugged end of the rod. During this operation the temporary plug in the center of the rod is cut away along the lines where the longitudinal channels are formed thus 60 dividing this core into five parts that readily fall out of the hollow center of the rod after the milling operation is completed. This leaves the rod with five equally spaced thin partitions or tines which are grouped around 70 the hollow center or pocket 71 of the rod 70 and form the individual blades illustrated in Figures 4 to 7 inclusive.

The method of forming the complete needle as above described is necessary because 75 in the milling operation for forming the blades the rod would not retain its shape without having a solid center into which the cutter can cut and steady itself with the tines during the cutting operation.

On the other hand, if the rod was not drilled before forming the blades, the solid center between the blades could not be made hollow afterwards on account of the small amount of metal left in the middle of the 80 rod after the cutting operation has been completed.

The blades or tines formed on the needle in this manner are thin and of equal thickness throughout their length. The inwardly 85 slanting and pointed outer end of each of the blades is provided with a cutting edge so that in entering the fruit the skin thereof is punctured and slit and is not torn. The body of each of the blades is made thin 90 enough so that in entering the fruit through the slits made by the pointed and sharpened ends thereof, the slits are not made larger and do not tear the skin. The blades are stiff enough to avoid spreading over the pit 95 but push out the pit ahead of them on the downward movement and maintain sufficient engagement with the pulp to lift it after the pit is pushed out through the bottom of the fruit. This leaves but five slits in the bottom 100 of the fruit when the needle is withdrawn after the pit or stone has been removed by pushing it through the top or stem end of the fruit and these slits readily close 105 up and are practically invisible after the 110

fruit has been canned and sealed in the glass jars. The skin in the top of the fruit is ruptured by the passage of the pit and the tines of the needle but because of the support given to the fruit by an elastic dia-
phragm the injury does not change the shape or impair the appearance of the fruit. The needle is set in a plunger, being fastened therein by a set screw, the needle bar hav-
ing a flat side provided thereon for the en-
gagement of the screw.

I claim:

The process of making a needle for pitting fruit which consists of first drilling the needle bar centrally from one end thereof and 15 forming a hole therein, then plugging the hole and milling a series of flat blades between the plug and the periphery of the bar and then withdrawing the plug.

In testimony whereof I affix my signature.

JOHN C. BAUMER.
